UNITED STATES PATENT OFFICE.

JAMES W. RUMSEY AND WILLIAM H. SHEASBY, OF CHICAGO, ILLINOIS.

COMBINED HANDLE AND LOCK FOR CAR-DOORS.

1,079,923.

Specification of Letters Patent.

Patented Nov. 25, 1913.

Application filed February 12, 1913. Serial No. 747,965.

To all whom it may concern:

Be it known that we, JAMES W. RUMSEY and WILLIAM H. SHEASBY, citizens of the United States, and residents of Chicago, 5 county of Cook, and State of Illinois, have invented certain new and useful Improvements in Combined Handles and Locks for Car-Doors, of which the following is a full and clear specification, reference being had 10 to the accompanying drawings, in which—

Figure 1 is a side elevation of a portion of a freight car siding and a portion of the rear edge of an edgewise movable car-door showing this invention applied thereto; 15 Fig. 2 is a vertical section on the line 2—2 of Fig. 1; Fig. 3 is a horizontal section on the line 3—3 of Fig. 1; Fig. 4 is a detail perspective of the lock block or keeper; and Fig. 5 is a detail perspective view showing 20 one way of making the lock block or keeper integral with the wear-rail.

The object of this invention is to provide a simple device which will automatically lock the door either in a fully closed or 25 a fully opened position, the locking device being adapted to be used as a handle or lever when in unlocked position for convenience in sliding the door back and forth, as more fully hereinafter set forth.

30 In the drawing *a* designates a part of a freight car siding and *b* an adjacent portion of the rear edge of a sliding freight car door. Set in a vertical slot cut in the door near its rear edge is a metal casing *c*, this 35 casing being rigidly fastened to the door by means of a series of bolts *d*, these bolts being passed through the door body and through the bottom wall *e* of a depending trough-like extension *f* of the lower wall. 40 of the casing *c*, this trough-like depending member being countersunk in the face of the door. The nuts *g* on the bolts *d* bear against the bottom wall *e* of the trough and lie wholly within the trough. The casing *c* 45 and its trough-like extension are provided with a continuous integral marginal flange *h* which bears solidly against the front face of the door.

The headed ends of the bolts *d* pass 50 through the metal weather strip *i* fastened to the rear face of the door. On a horizontal pivot *j* extending across the casing *c* is pivoted a locking lever whose upper end or nose *k* extends inwardly beyond the rear 55 face of the door and is adapted to engage

either one or two locking blocks or members *l* fastened to the car body. The handle part *m* of the lock lever depends from the pivot, that is, lies approximately at right angles to the lock nose *k* and is adapted when the door is locked in either position, to lie within the trough member *f*, its inner face abutting against the bottom wall *e* of the trough. Suitable recesses *n* in this lever *m* are provided for the reception of the nuts *g*, and a 60 finger piece or extension *o* is provided at the lower end of the lever, this finger piece extending to a point below the lower end of the trough or channel *f* for convenience in lifting the lever out of the trough or channel. A staple or perforated lug *p* projects 65 forwardly from the bottom of the channel member *f* and extends through the registering opening in the lock lever *m*, the lever being provided with a pair of perforated 70 ears *q*, whereby the seal wire may be passed through the corresponding holes or openings in the three lugs or ears, thus locking the lever *m* down in the trough or channel. The 75 lower outer corners of the keeper blocks *l* 80 are each beveled off to form a cam surface *r*, for the purpose hereinafter set forth, and fastened to the car body is a metal wear strip *s*, this strip extending from a point 85 near the left hand door post *t* to a point 90 near the usual door stop *u* fastened to the car body. This strip is fastened to the car body at a point just below the lock stops *l*, and these stops *l* are fastened to the car body at points adjacent to the respective 95 ends of this wear strip. In Fig. 5 I show the lock stops or members formed integral with the wear strip, the end of the strip being bent or extended upwardly and forwardly upon itself to form a stop or block *l'*. 95 Any other suitable manner of forming these blocks integral with the wear strips may be employed, as is evident.

It will be observed that the handle end of the locking device is heavier than the 100 bolt or nose end thereof and that therefore the tendency of the handle is to fall by gravity; and it will also be observed that by reason of the location of the pivot *j* at the point shown this handle member normally 105 rests against the bottom wall *e* of the channel *f*, where it will be flush with the adjacent edges of the fixed member of the device, this member consisting of the casing *c* and the channel member depending therefrom. 110

With this weighted handle member it will be seen that the normal tendency of the lock bolt or nose *k* is to swing upwardly, so that the device will automatically lock the door 5 either in a closed position or in its full open position.

The gravitation of the handle end of the locking member causes the locking nose or bolt to swing up behind the keepers or lock 10 stops *l* and thus lock the door in either a closed or an open position. When the handle is raised to unlock the door it will be seen that the proportions of the parts are such that by the time the lock nose *k* has 15 been swung down sufficiently to pass by the keeper *l* it will lie in a plane in front of the wear plate *s*, so that when the door is moved in either direction the lock nose will pass in front of this plate *s*, so that should the operator release the handle or bear down upon it in the act of shoving the door in either direction the lock nose will bear against the strip *s* and slide therealong. This will 20 prevent the lock bolt from impinging against the car body and thus scratching the pin therefrom or catching into the car body and interfering with the free movement of the door. This coöperation of the wear plate and the lock nose will also prevent the handle dropping to locking position until the door is either fully opened or fully 25 closed, so that not only will the handle be available as a handle for sliding the door during the whole time that it is partly open but it will be seen also that this provision 30 will unfailingly apprise the attendant and other persons who have an interest in knowing the fact that the door is either open or fully locked in one position or the other.

40 A feature of importance lies in the fact that when the device is in locking position, the gravitating handle entirely covers the outer ends of the fastening bolts and the nuts thereon, so that it will be impossible for 45 the lock to be disconnected from the car without first breaking the seal wire, which is passed through the holes in the lugs *p* and *q*. In this way unauthorized or burglarious opening of the door is rendered impossible without breaking the car seal. The 50 advantage in the beveled corners *r* of the keepers *l* is that these bevel faces coöperate with the locking nose when the same is swung upwardly into locking position and 55 act as cams to assist in forcing the door to a tight closure or to a full open position.

It will be observed that it is important 60 that the parts shall be so proportioned that when the handle is raised to unlock the door the locking nose shall by the time it has passed below the lower edge of the keeper blocks *l* be in position to engage with the front face of the wear strip *s* when the door is moved slightly in the direction toward the adjacent end of the strip, whereby it will

be impossible to move the door from its locked position without at the same time engaging the lock nose with the wear strip, whereby it will be rendered absolutely certain that when the door is unlocked the handle shall be held in a raised position and whereby also it will be impossible to slide the door in either direction without protecting the car body against the impingement of the locking nose or bolt. 70

A further feature of advantage is that we so locate the stationary member of the device that its fastening bolts *d* shall not only pass through the car door body but also through the closure iron strip *i* fastened to the inner 80 face of the door, whereby the locking device is fastened and anchored in a rigid manner, enabling it to withstand the roughest kind of service abuse. 75

Having thus described our invention, 85 what we claim as new and desire to secure by Letters Patent, is—

1. In combination, a sliding car door, a metal casing fitted into a recess in the door and having a depending channel portion 90 likewise fitting into a recess in the face of the door, means for fastening the casing to the door, the bottom of the said channel portion being provided with an upstanding seal-wire-receiving lug, a combined lock 95 and handle pivoted in the casing and having a depending handle portion adapted to fit and lie in said channel portion, this handle being provided with a hole through which the aforesaid lug projects and also with adjacent seal-wire-receiving lugs, for the purpose set forth. 100

2. In combination, a sliding door, a casing fitted into the face thereof and provided with a depending channel portion likewise 105 fitted into the face of the door, bolts passing through the bottom wall of said channel portion and adapted to fasten the casing to the door, said bolts being provided with nuts on their outer ends which lie in said channel 110 portion of the casing, a combined lock and handle pivoted to the casing and having a depending handle portion which is adapted to lie within said channel portion when the door is locked, this handle portion serving 115 to cover the bolts and nuts and being provided with recesses for the projecting ends of the bolts and the nuts, and means whereby a seal wire may lock the handle in its down position. 120

3. In combination with a car door, a casing fastened thereto, a combined lock bolt and handle pivotally mounted in the casing, said handle being adapted to swing down toward the door to bring the lock bolt into locking position, a series of fastening devices for said casing located all in vertical alinement so as to be covered by said handle when the same is in its down position. 125

4. In combination, a car door provided 130

with an opening, a casing set into said opening and having a depending channel portion embedded in the face of the door, a horizontal pivot *j* extending across the casing, a 5 freely-swinging combined lock bolt and handle mounted on said pivot, the handle member being adapted to depend from the pivot when in locking position and to lie within the aforesaid channel portion of the 10 casing, the handle member and the casing being provided with seal-wire-receiving lugs.

5. In combination, a car door, a casing set thereinto and a vertical series of devices 15 for fastening the casing to the door, said casing being provided with a depending channel or trough also set into the door, and a combined lock and pendant handle, the handle being adapted to close down into 20 and lie in said channel, said fastening means being in vertical series in said channel so as to be all covered by said handle when the same is in locking position.

6. In combination with a car body having 25 affixed to it a pair of separated stops and a wear plate extending between and below said stops, of a sliding car door carrying a lock bolt adapted to engage behind either one of said stops and to ride along the outer 30 face of said wear plate, said lock bolt being provided with a gravitating handle.

7. In combination with a car body provided with a pair of stops one at each end of the travel of the door and an intermediate 35 wear strip, of said door and a combined lock bolt and handle carried by said door, said lock bolt being adapted to engage behind

either of the stops and ride along against the face of the wear plate.

8. In combination with a car body, a pair 40 of lock stops affixed thereto at each end of the travel of the car door, and a wear strip affixed to the car body below said stops and extending to near the operative faces of 45 said stops, of a sliding car door and a combined lock bolt and handle pivoted thereon, the handle having a preponderating weight so as to normally tend to gravitate to locking position, said lock bolt extending through the car door and beyond the 50 inner face of the car and being adapted to swing from behind either one of the lock blocks to a position in front of the wear plate, whereby the wear plate will lock the handle in its raised position during the 55 movement of the door.

9. In combination with a car body provided with a pair of stops one at each end of the travel of the door and an intermediate wear strip, of said door and a combined lock bolt and handle carried by said door, said lock bolt being adapted to engage 60 behind either of the stops and ride along the face of the wear plate, said stops having their lower outer corners beveled to coöperate with the adjacent part of the lock bolt.

In testimony whereof we hereunto affix our signatures in the presence of two witnesses this 10th day of Feby. 1913.
